Attorney.

UNITED STATES PATENT OFFICE.

OLIVER B. BRADFORD, OF BEAVER FALLS, PENNSYLVANIA, ASSIGNOR OF ONE-HALF TO WILLIAM A. McCOOL, OF SAME PLACE.

SHOE.

SPECIFICATION forming part of Letters Patent No. 392,404, dated November 6, 1888.

Application filed November 19, 1887. Serial No. 255,641. (No model.)

To all whom it may concern:

Be it known that I, OLIVER B. BRADFORD, of Beaver Falls, in the county of Beaver and State of Pennsylvania, have invented certain new and useful Improvements in Shoes; and I do hereby declare the following to be a full, clear, and exact description of the invention, such as will enable others skilled in the art to which it pertains to make and use the same.

10 My invention relates to shoes, and more particularly to shoes having the soles, heels, taps, legs, or other parts made of fire-proof material.

It is well known that in rolling-mills, foundries, furnaces, and like establishments the 15 shoes of the workmen are frequently burned by the treading upon heated scraps of metal, &c.

The object of my invention is to provide a 20 shoe for the purpose stated that will be efficient and durable.

In the accompanying drawings, Figure 1 shows a shoe provided with a sole made of my improved fabric. Fig. 2 is a cross-section of the shoe-sole.

25 A represents the sole of a shoe.

A' represents a wire-netting bent, woven, or in any suitable manner brought to the required shape.

B is a filling of asbestos. This filling is 30 caused by pressure to enter the spaces between the wires, and the filling thus combines with the netting to form a hard, rigid, yet flexible, fabric, well adapted for shoe-soles.

It will be apparent that I may use wire-netting of different sizes and grades to make different grades of my improved material. For instance, for making shoe taps or legs a lighter fabric would be used than for shoe soles or heels.

40 I do not limit myself to any particular con-

figuration of wire-netting, nor to any specific method of shaping the material.

I also desire to have it understood that my invention comprehends the use of any fire-proof filling and is not restricted to the use of 45 asbestos, as many fire-proof compositions could be used satisfactorily.

If desired, an entire foot-covering—such as a slipper or moccasin—might be made of my fire-proof material, with a leg or leggins attached or detached.

In the drawings I have shown, for convenience, only the sole of a shoe made in accordance with my invention; but it will be understood that I contemplate making the shoe either 55 partially or wholly of said material, or any part desired.

Having fully described my invention, what I claim as new, and desire to secure by Letters Patent, is—

1. As an improved article of manufacture, an outer sole for boots or shoes comprising a wire frame presenting the configuration of the sole, and a filling of fire-proof material located within the interstices of the frame to form contact-faces for the sole, substantially as set forth. 65

2. The combination, in a boot or shoe, of an outer sole comprising a wire frame presenting the configuration of the sole, and a filling of asbestos located within the interstices of the 70 frame to form contact-faces, substantially as set forth.

In testimony whereof I have signed this specification in the presence of two subscribing witnesses.

OLIVER B. BRADFORD.
